R. E. CHATHAM

SIGNAL DEVICE FOR RAILWAYS

Filed Sept. 21, 1925

Robert E. Chatham,
Inventor

John M. Spellman
Attorney

UNITED STATES PATENT OFFICE.

ROBERT E. CHATHAM, OF DALLAS, TEXAS.

SIGNAL DEVICE FOR RAILWAYS.

Application filed September 21, 1925. Serial No. 57,573.

This invention relates to improvements in railway signals and in such connection it relates more particularly to that part of the signal apparatus which provides the connection between the track and the wired connections leading to the semaphore, or the like.

The principal object of the invention is to provide a simple and effectual attachment 10 for railway rails arranged in the path of the wheel flange so that the wheel or wheels will ride thereon and depress the attachment and make the connection to the semaphore. The attachment is also arranged so 15 as to provide a single or double circuit as desired, both circuits being operable in the same manner as the car wheel travels over the attachment. The invention provides in its arrangement and parts means for protecting the contact parts and is otherwise 20 strong and durable.

With the above and other objects in view, the invention will be more clearly understood from a perusal of the following description taken in connection with the accompanying drawings, forming part hereof and in which:—

Figure 1 is a side elevational view of a portion of a railway rail and illustrating 30 the attachment in operable position on the rail.

Figure 2 is a vertical sectional view of the attachment along the line 2—2 of Figure 1.

Figure 3 is a similar view along the line 3—3 of Figure 1.

Figure 4 is a detailed sectional view showing a modification of a double contact.

In carrying out the invention, there is 40 provided an angle iron 1, the lower portion so shaped as to be conformably seated upon the base 2 of the rail, the upper surface of the angle iron providing a horizontal surface in parallel relationship to the head 4 of the rail. The rear surface of the angle iron is slightly depressed at 5 so that when tightened against the web 6 of the rail it will provide a gripping effect.

Upon the upper surface 3 of the angle 50 iron is supported a rocker arm 7 which has a rounded portion 8 and a rounded head 9. The rocker arm 7 is secured to a vertical leg 10 by screws 11, the leg projecting downward in front of the base 2. The rocker arm 85 is connected to the rail by a bolt 12 passed therethrough and through the angle iron

and the web 6. A lock-nut 13 holds the rocker arm in place.

Underneath the rail base 2 are insulating plates 14 interposed between which is a 60 metallic contact plate 15 connected to a wire 16. A wire 17 connected to the web 6 completes a wired circuit for an electric source of power to operate the semaphore or signal.

The illustration in Figure 2 shows a single circuit arrangement while Figure 4 illustrates a double circuit, with contact plates 18—18 and insulating plates 19. A support 20 is secured to the lower portion 1 of the angle iron and to the rail base 2 on one 70 side by a plate 21 and a similar plate 22 secures the rail base 2 to the support 20 on the opposite side. The aperture 23 in the rocker arm 7 permits the latter to move freely.

In operation, the wheel 24 of the locomotive will ride upon the rocker arm head 9 which will rock the same into the position shown by dotted lines in Figure 1. As the wheel moves fairly upon the rocker arm the 80 leg 10 will depress the contact plate and connect the circuit to operate the signal.

It should be understood that the invention is not limited to the particular construction shown in the drawings for carrying out 85 the invention, but that changes may be made as desired in keeping with the spirit of the invention and also such equivalents pertaining to the art as set forth in the following claims.

I claim:—

1. In a railway signal contact device, a rocker arm, a support therefor, said support and arm connected to a railway rail by a bolt, a lock-nut on the outer end of the bolt, said rocker arm having an opening of larger diameter than the bolt to permit the rocker arm to move freely upon the bolt and its support; said arm having an enlarged and rounded head portion on one end and an under-projection, the latter adapted to permit the arm to rock upon its support; a leg on the arm, contact plates and a support therefor underneath the leg, and a wire connected to said rail and contact plates.

2. In a railway signal contact device, a rocker arm, a support therefor, said support and arm connected to a railway rail, said arm having an enlarged head portion and a rounded under projection, said projection 110 enabling the arm to rock upon its support, means for pivotally locking the arm and se-

curing its support to a railway rail; a leg on the arm, contact plates and a support therefor underneath the leg and a wire connected to the rail and contact plates; said leg and plates adapted to be moved together as the railway equipment passes over the rail.

3. In a railway signal contact device, an arm and a support therefor attached to a railway rail, said arm having a rocker thereon; a leg depending from the arm, contact plates and a support therefor beneath

the leg; insulating elements between the plates; wires connected to said rail and said plates; and a brace on each side of the rail 15 to hold the plate supporting element to the rail, said leg arranged to be pressed downward as the railway wheels ride upon the arm and cause the leg to be moved against the contact plates to close an electric circuit in a signal apparatus. 20

In testimony whereof I affix my signature.

ROBERT E. CHATHAM.
